UNITED STATES PATENT OFFICE.

WILLIAM B. TABOR, OF NEW DOUGLAS, ILLINOIS, ASSIGNOR OF ONE-HALF TO ALBERT D. MARTIN, OF GILLESPIE, ILLINOIS.

STOP SIGNAL FOR CROSSINGS.

Application filed May 23, 1922. Serial No. 562,964.

To all whom it may concern:

Be it known that I, WILLIAM B. TABOR, a citizen of the United States, and resident of the city of New Douglas, county of 5 Madison, and State of Illinois, have invented certain new and useful Improvements in Stop Signals for Crossings, of which the following is a specification containing a full, clear, and exact description, reference being had to the accompanying drawings, forming a part thereof.

My invention relates to improvements in stop signals for crossings, and has for its primary object a signal which will automatically indicate a stop or flash a danger signal for railway crossings whenever a car or train of cars approaches within a predetermined distance of said crossing.

A further object is to construct a stop 20 or danger signal for railway crossings which is operated automatically by the passage of cars on the right of way of railway, but one which will not obstruct traffic over the crossing in the event that the approaching vehicle is too close to come to a stop.

My device is intended to obviate the use 30 of crossing switch men and gates across railway crossings, which obstruct the railroad and prevent the passage of vehicles, which has frequently happened where crossing gates are made use of, and the gates consequently lowered that a vehicle approaching a crossing was traveling at such a rate of speed as to prevent its being 35 stopped, in which case it crashed into the gates, frequently injuring the passengers of the vehicle, and at times injuring the vehicle to such an extent that it came to a stop directly in the path of the approaching 40 danger.

By the use of my device the vehicles are properly warned, but at the same time permitted the free passage in the event that they are too close to the crossing at the time 45 the signal is flashed to cross the danger point.

In the drawings,

Fig. 1 is a side elevation of my device with the crossing signal tripped.

Fig. 2 is a top plan view of the same.

Fig. 3 is a cross section taken on the line 3—3 of Fig. 2.

Fig. 4 is a bottom plan view showing the latching or holding mechanism.

Fig. 5 is an enlarged fragmental sectional view of the latching mechanism.

Fig. 6 is an enlarged fragmental sectional view of one of the tripping levers.

In the construction of my device 7 represents the railway tracks, 8 the ties, and 9 the crossing. At each end of the crossing are erected posts 10, to which is secured a sign board 11, bearing a suitable inscription so as to notify the passengers on the highway that they are approaching a railway crossing. On each side of the crossing 9 are arms or bell crank levers 12 which are joined at their top ends by a sign board 13. This sign board has preferably imprinted or painted thereon, the words "Stop, danger," 70 and also bears a red light or danger signal 14. The opposite ends of the arms 12 are secured to a shaft 15 which is mounted in bearings secured to certain of the ties 8. These arms 12 are secured either by means 75 of pins driven through the arms and shaft, or by any other suitable means, so that the shaft cannot rotate without operating the arms. Centrally of the shaft 15 and secured in a similar manner is a sleeve 16. 80 This sleeve has a horizontal projecting portion 17 which projects beneath the base flange of the rails 7. The portion 17 has a vertical extending portion 18 which terminates in a flat plate 19. This flat plate is 85 for the purpose of engaging the flanges of the railway car. The portion 17 has an integrally formed tooth or projection 20 which engages with the latch 21. This latch is secured in a housing 22, which housing 90 is mounted between two of the ties. The latch 20 is controlled or moved forward by means of a coil spring 23. Secured to the latch 21 is a pin 24 which projects through a slot 25 formed in the housing 22, and to 95 the pin 24 is secured a cable or other flexible means 26. This cable passes around a pulley 27 secured to the housing 22, its free end is secured to a rod or cable 28. The opposite end of the rod or cable 28 is secured 100 to the end 29 of the trip lever 30. This trip lever is pivotally mounted at a point 31 in the bracket 32 and this bracket 32 is secured to the railway ties at any predetermined distance from the crossing. Surrounding 105 the rod or cable 28 are coil springs 33 and 34. The purpose of the spring 33 is to pull the rod 28 backward and assist in relieving

the spring 23, while the purpose of the spring 34 is to allow the lever to be tilted in the direction indicated by the arrow "B" in Fig. 6, and return it to its original position. The arrow "A" in the same figure, indicating the direction in which the lever is operated to trip the signal. In other words, the springs 33 and 34 tend to hold the trip lever 30 in its operative position at all times. Adjacent the vertical projections of the signal arms are blocks or bumpers 35 which control the tripping of the signal arms. In other words, limit the distance of their downward movement.

15 The operation of my device is as follows: After the device has been properly installed at a crossing, the arms 10 are lifted upward. This movement engages the tooth 20 with the latch 21 and supports the 20 warning signal 13 in raised position, so that it will be hidden by the board or sign 11, (see dotted lines, Fig. 3.) If a vehicle on the right of way of the railway is approaching from either direction, it will 25 strike the trip lever 30 when reaching a predetermined distance from the crossing. This movement of the trip lever 30 will operate one of the rods 28, withdraw the latch 21, and release the tooth 20. This 30 allows the bell crank levers or arms 12 to trip, carrying with them the danger signal or board 13, which becomes visible beneath the board 11,—thus warning the traffic that there is danger in crossing. This tripping 35 of the signal alarm will raise the plate 19, as indicated by dotted lines in Fig. 5. As soon as the vehicle on the tracks reaches this plate, the wheel flanges thereof will contact with the plate and force it downward so that the tooth 20 can again engage 40 with the latch 21, thus automatically resetting the signal,—its continued movement will trip the opposite lever 31, but this movement being in the retrograde will not 45 again trip the danger signal. The light 14 may be ignited every night by a section hand, or it may be an electric light which will automatically light when the signal has been lowered. This may be accomplished 50 in various ways. The operating lever is so constructed as to extend upward between the tracks and engage either with the cow catcher, fender, or axles of a railway coach, and is only designed to trip the danger 55 signal when struck in the direction indicated by the arrow "A" in Fig. 6. The opposite direction indicated by the arrow "B" having no effect on the tripping of the danger signal,—while the restoring of the signal 60 to a clear passage over the right of way by the action of the flanges of the wheels is accomplished only when the wheels pass the center of the crossing, so that there is no possibility of the device being set at the 65 clear crossing while the railway coach is

on either side of the crossing, so that my device will register at danger until the crossing is entirely clear, of course, where a freight or passenger train is travelling over the crossing, the device will be tripped by the locomotive when coming within a predetermined distance of the crossing, and as soon as the front truck of the engine strikes the plates 19, the crossing will again show clear, but in this event, the crossing will still be blocked by the remaining coaches or cars being drawn by the locomotive, so that there is no danger of a vehicle attempting to cross over.

Having fully described my invention, what I claim is:

1. A stop signal for railway crossings comprising in combination with a railway track and ties, a bearing secured to said ties and on each side of the crossing, a shaft 70 mounted in said bearings, a bell crank lever located on each side of the crossing and having one arm thereof secured to said shaft, a sign board secured to the other end of said levers and extending across the 75 crossing, a sleeve secured to said shaft midway its ends, a horizontal projecting portion formed integral with said sleeve and extending beneath the base flange of the 80 rails, a vertical portion terminating in a flat plate formed integral with the horizontal portion and lying along the inside edge of the ball of the rail, a tooth formed integral with the horizontal projecting portion, a spring actuated latch adapted to 85 engage with said tooth, a lever located between said tracks on each side of the crossing and at a predetermined distance therefrom, a rod secured to said lever, cables secured to said rod and latch, and a fixed 90 sign extending across said crossing, said fixed sign normally covering the sign board carried by the bell crank levers.

2. A stop signal for railway crossings comprising in combination with a railway track and ties, a bearing secured to certain of said ties on each side of the crossing and on each side of the track, a shaft mounted in said bearing, a bell crank lever located 100 on each side of the crossing and having one arm thereof extending horizontally and secured to the shaft, the other arm extending vertical, a sign board to the vertical arms of said levers and extending across the 105 crossing, a sleeve secured to said shaft midway its ends and having a horizontal portion formed integral therewith, said horizontal portion extending beneath the base flange of the rails, a flat plate formed integral with said horizontal portion and lying along the inside edge of the ball of the rail, said flat plate adapted to be contacted with by the flange of the railway wheel, a tooth formed integral with the horizontal portion, a spring actuated latch adapted to 110

engage with said tooth, a lever located between said tracks and at a predetermined distance from each side of the crossing, a rod secured to one end of said lever, springs surrounding said rod and adapted to normally hold the lever in vertical position, cables attached to said rods and said latch, said cables adapted to operate said latch when the lever is operated in one direction only and allowing the lever to operate in the

opposite direction without any effect on the latch, and a fixed sign extending across the crossing, said sign normally tending to cover the sign board carried by the bell crank levers whereby the same will only 15 become visible when the latch and the tooth have been disengaged.

In testimony whereof, I have signed my name to this specification.

WILLIAM B. TABOR.
